(57) **CLAIM**

We claim the ornamental design for a jar with lid, as shown and described.

DESCRIPTION

FIG. 1 is a perspective view of a front, a top, and a left side of a jar with lid, in accordance with a first embodiment of the design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of a rear, a bottom, and a right side thereof;

FIG. 9 is a left side view thereof, shown in a state with the lid removed from the jar;

FIG. 10 is a perspective view of a front, a top, and a left side of a jar with lid, in accordance with a second embodiment of the design;

FIG. 11 is a front view thereof;

FIG. 12 is a rear view thereof;

FIG. 13 is a left side view thereof;

FIG. 14 is a right side view thereof;

FIG. 15 is a top view thereof;

FIG. 16 is a bottom view thereof;

FIG. 17 is a perspective view of a rear, a bottom, and a right side thereof; and,

FIG. 18 is a left side view thereof, shown in a state with the lid removed from the jar.

The broken lines shown in the drawings illustrate portions of the jar with lid and form no part of the claimed design.

The jar of the jar with lid is entirely transparent, and the oblique line shading shown in the drawings illustrate the transparency of surfaces of the jar.
